UNITED STATES PATENT OFFICE

MICHAEL MATTHEW BASAR, JR., OF OMAHA, NEBRASKA

STOCKING PROTECTOR

Application filed September 17, 1928. Serial No. 306,407.

My invention relates to stocking protectors and has particular reference to an improved protector adapted to be mounted within the counter portion of a shoe or slipper 5 to eliminate the friction and wear which ordinarily exists between the heel portion of the stocking and the adjacent inner surface of the counter portion of the shoe or slipper.

An object of my invention is to provide a 10 stocking protector which will take up or compensate for the relative movement between the heel of the wearer and the counter portion of the shoe, thereby effectively preventing the wearing out of the heel portion of the 15 stocking and preventing the formation of blisters on the heel of the wearer.

A further object of my invention is to provide a stocking protector adapted for mounting within a shoe or slipper, said protector 20 including a member rigidly attached to the rear, inner surface of the counter, and a second member attached to said counter and to said first member and capable of relative movement with respect to the first member, 25 the relative movement between the two members eliminating the friction and wear which ordinarily exists between the heel portion of the stocking and the adjacent inner surface of the counter of the shoe or slipper.

30 A still further object of my invention is to provide a stocking protector which is easy to mount within the shoe, and which is simple in construction, cheap to manufacture, reliable in operation, and highly efficient in the 35 purpose for which designed.

In the accompanying drawings forming a part of this specification and in which like numerals are employed to designate like parts throughout the several views,

40 Fig. 1 is a perspective view of the rear portion of a shoe or slipper, showing my improved stocking protector mounted therein;

Fig. 2 is a rear view of one of the protectors;

45 Fig. 3 is a front view, partly in section, of one of the protectors;

Fig. 4 is an enlarged vertical sectional view through one of the protectors;

50 Fig. 5 is a plan view showing a convenient and preferred manner of temporarily mount-

ing a pair of protectors for display and sale purposes, and,

Fig. 6 is a perspective view of each of the three members which enter into the construction of my improved protector.

Referring to the drawings, wherein for the purpose of illustration is shown a preferred embodiment of my invention, the numeral 1 designates a shoe or slipper of any conventional or preferred type or style, within the counter portion of which is mounted one of my improved stocking protectors 2. Each of these protectors comprises three members, as best illustrated in Fig. 6 of the accompanying drawings, in which figure the 65 numeral 3 designates a strip of fabric, preferably plush, velvet or other pile fabric, having its ends 4 and 5 folded over and spaced as shown. The second member of the protector comprises a substantially square piece 70 of celluloid, pasteboard, fiber board or other relatively stiff material 6, of a width somewhat less than the width of the flexible strip 3 and of a height somewhat less than the vertical dimension of the front face of the 75 flexible strip 3, but greater than the distance or space between the over-turned ends 4 and 5 of said flexible strip. The third member 80 of the protector comprises a strip of adhesive tape 7, folded over into a loop with overlapping edges and flattened as shown, it being noted that the adhesive side of this strip is on the outside. The vertical dimension of this folded and flattened loop 7 is approximately the same as the vertical dimension 85 of the member 6, and is therefore greater than the distance between the overturned ends 4 and 5 of the strip 3.

In assembling my improved protector, the square 6 is placed adjacent the inner surface 90 of the strip 3 and the ends 4 and 5 folded over to engage the rear surface of said square, it being noted that there is an appreciable space or distance between the upper and lower edges of the square 6, and the upper and lower lines of fold defined by the overturned ends 4 and 5 respectively. The flattened loop 7 of adhesive is next placed adjacent the rear surface of the square 6, with its upper and lower edges overlapping the outer faces of the over- 100

turned edges 4 and 5 of the flexible strip 3. The parts are then pressed together, and when so assembled, the adhesive strip functions to hold the plate or square 6 and the flexible strip 3 in proper assembled relation but, due to the space between the upper and lower edges of the square or plate 6 and the upper and lower lines of fold normally defined by the overturned ends 4 and 5 respectively, the front surface of the strip 3 is capable of limited movement with respect to the square or plate 6. The rear surface of the adhesive strip 7 provides a convenient means of attaching the entire device within the counter of a shoe or slipper as shown in Fig. 1, and when so attached said strip maintains the square or plate 6 in fixed position within the said counter but permits relative movement between the flexible strip 3 and the said square or plate 6.

In Fig. 5 of the accompanying drawings, I have shown a convenient means for displaying and dispensing a pair of my improved protectors, and in this view the numeral 8 is used to designate a sheet of paper, cloth, metal or other material, upon which two of the protectors are temporarily mounted. The sheet 8 is preferably somewhat larger than the combined area of two of the protectors to thus protect the marginal edges of the protector. The protectors are mounted upon the sheet 8 and are held thereon by the adhesive strip 7, it being understood that the bond between the sheet 8 and the adhesive strip 7 can be readily broken when it is desired to remove the protectors from the sheet to apply the protectors within the shoe or slipper.

Referring now to the operation of my improved protectors when placed within the counter of a shoe, the adhesive strip 7 holds the entire protector in place within the counter portion and maintains the square or plate 6 in fixed position with respect to the said counter. Due to the space between the upper and lower edges of the square or plate 6 and the normal lines of fold defined by the overturned edges 4 and 5 of the flexible strip 3, the front surface of said strip is permitted to partake of limited movement with respect to the said stationary square or plate 6. As above stated, the strip 3 is made of a pile fabric, such as velvet, plush, or the like, and the outer face of the strip is in direct engagement with the heel portion of the stocking when the shoe or slipper is on the foot of the wearer. The ordinary rubbing action which generally takes place between the heel of the stocking and the inner surface of the counter 60 is therefore compensated for by the movement of the flexible strip 3, which is in direct contact with the heel of the stocking, and the stationary square or plate 6, and hence the friction and wear between the stocking and counter is completely eliminated and com-

pensated for by the movement between the strip 3 and the square or plate 6. Due to the fact that the outer surface of the strip 3 is of pile fabric, there is no relative movement between the heel of the stocking and the said strip and the only movement occurs between the said strip and the plate 6. Hence all tendency toward the wearing out of the heel of the stocking or the formation of blisters on the foot of the wearer is effectively overcome. Due to the fact that the parts of the device are all relatively thin, the protector is not at all bulky or cumbersome when placed within a shoe or slipper and will not force the foot forward within the shoe. The engagement between the flexible strip 3 and the heel portion of the stocking also prevents any tendency for the shoe or slipper to slip off of the foot of the wearer, which is sometimes the case when the shoe is too large.

It is to be understood that the form of my invention herein shown and described is to be taken as a preferred example of the same, and that various changes in the shape, size, and arrangement of parts may be resorted to without departing from the spirit of the invention or the scope of the subjoined claims.

Having thus described the invention, I claim:

1. A stocking protector comprising a plate attached to the inner surface of the counter of a shoe, and a strip of fabric overlying said plate and having a portion engaged by the heel of the stocking and capable of movement therewith, said fabric partaking of limited movement with respect to the said plate.

2. A stocking protector comprising a plate attached to the inner surface of the counter of a shoe, a strip of fabric having a portion attached to the plate and a portion engaged by the heel of the stocking and capable of movement therewith.

3. A stocking protector comprising a plate attached to the inner surface of the counter of a shoe, a strip of fabric having overturned ends secured to the inner surface of the counter of the shoe, the intermediate portion of said strip overlying said plate and being engaged by the heel of the stocking and being capable of movement therewith.

4. A stocking protector comprising a plate attached to the inner surface of the counter of a shoe, a strip of fabric having overturned ends secured to the plate and to the inner surface of the counter of the shoe, the intermediate portion of said strip overlying said plate and being engaged by the heel of the stocking and being capable of movement therewith.

5. A stocking protector comprising a plate, a strip of fabric overlying said plate and capable of limited movement with respect thereto, and a strip of adhesive tape attached to the plate and strip to hold the two in as-

sembled position and by means of which the plate and fabric are attached to the inner surface of the counter of a shoe.

6. A stocking protector comprising a plate, 5 a strip of fabric overlying the plate and having its ends folded over the upper and lower edges of said plate with a space between the upper and lower edges of the plate and the normal lines of fold of the folded-over portions whereby the strip can partake of limited 10 movement with respect to the plate, and means for attaching the plate and strip within the counter of a shoe.

7. A stocking protector comprising a plate, 15 a strip of fabric overlying the plate and having its ends folded over and attached to the upper and lower edges of said plate with a space between the upper and lower edges of the plate and the normal lines of fold of the 20 folded-over portions whereby the strip can partake of limited movement with respect to the plate, and a strip of adhesive tape connected to said plate and by means of which the plate and strip are attached within the 25 counter portion of a shoe.

8. A stocking protector comprising a plate, a strip of fabric overlying the plate and having its ends folded over the upper and lower edges of said plate with a space between the 30 upper and lower edges of the plate and the normal lines of fold of the folded-over portions whereby the strip can partake of limited movement with respect to the plate, and a strip of adhesive tape connected to the folded-over ends of the strip and to the plate to hold the two in assembled position and by 35 means of which the strip and plate are attached to the inner surface of the counter of a shoe.

40 In testimony whereof I hereunto affix my signature.
